UNITED STATES PATENT OFFICE.

CHARLES F. STEVENS, OF CHICAGO, ILLINOIS.

FIRE-BRICK ARCH.

1,130,345.

Specification of Letters Patent.

Patented Mar. 2, 1915.

Application filed February 16, 1914. Serial No. 818,875.

To all whom it may concern:

Be it known that I, CHARLES F. STEVENS, a citizen of the United States, residing at Chicago, in the county of Cook and State of Illinois, have invented certain new and useful Improvements in Fire-Brick Arches, of which the following is a specification.

This invention relates to fire brick arches of the kind which are installed in fire boxes 10 or boilers, and other like places, and designed to withstand the heat from and deflect the products of combustion.

The invention has for its object the construction and installation of a fire brick arch which can be put in old as well as new constructions; which can be installed by placing the tiles forming the same separately in position and taken down by removal of said tile separately; and in case of 20 the breaking of the elements of the arch can be repaired without the removal of any considerable number of said elements.

A further object is to obtain flexibility in the arch by providing means whereby horizontal and vertical movements of the elements of the arch are permitted.

In the drawings which accompany and form a part of this specification Figure 1 is a vertical section on line 1—1 of Fig. 2, 30 viewed in the direction indicated by the arrows. Fig. 2 is a vertical section on line 2—2 of Fig. 1, viewed in the direction indicated by the arrows. Fig. 3 is a vertical section, on line 3—3 of Fig. 4, of a modification 35 of the construction illustrated in Figs. 1 and 2, viewed in the direction indicated by the arrows. Fig. 4 is a vertical section on line 4—4 of Fig. 3, viewed in the direction indicated by the arrows. Fig. 5 is a vertical 40 section on line 2—2 of Fig. 1, on an enlarged scale, and viewed in the direction indicated by the arrows in said Fig. 1. Fig. 6 is a side elevation of the tile suspending device which is illustrated in Figs. 1, 2, and 5, 45 viewed as in Fig. 1. Fig. 7 is a perspective of a member used with the suspending device when the supporting beams of the arch are I-beams. Fig. 8 is an elevation of the modification of the suspending device which 50 is required with a supporting I-beam. Fig. 9 is a vertical section of an I-beam, showing the suspending device attached thereto, in elevation. And Fig. 10 is a horizontal section on line 10—10 of Fig. 5, viewed in the 55 direction indicated by the arrows.

A reference character applied to designate

a given part indicates said part throughout the several figures of the drawings, wherever the same appears.

A are the side walls of a fire box.

B are U-shaped beams (channel beams), which are supported by the side walls A.

C, (Figs. 2, 4, 8 and 9) are I-beams.

B¹, (Figs. 3 and 4), are curved U-shaped beams which are supported by the side walls A, and are modifications of beams B.

D is an arch comprising the fire brick or tile d and the suspending devices d¹, d². Fire brick or tile d are respectively provided with the head d³. The sides of the fire brick or tile d are beveled, or on radial lines of the arch D, as shown by lines d⁴, Figs. 1 and 3; while the front and back faces thereof are substantially parallel, as shown by lines d⁵, Figs. 2 and 4. Suspending devices d¹ comprise the body member E provided with ratchet teeth e and heads e¹, e². Body member E is also provided with the slot e³. Said suspending device d¹ also comprises the elastic members F and bolt f, with nut f¹. Both ends of the elastic members F are turned. The turning of the upper ends of said members provides means to engage said members F with the ratchet teeth e on members E; and the turning of the lower ends of said members provides means of engaging said members with the under sides of the heads d³ of brick or tile d. An adjustment 70 of the members F on member E determines the vertical position, in the arch D, of the brick or tile d which is suspended thereby.

Member E is supported by the under side of the head e¹ resting on the lower flange of the U-shaped pieces; and said under side, or face, of said head e¹ curved to permit said head to rock on said flange. The incline desired in a given brick or tile is thus obtained. To insert the member d¹ in place it is turned so that the longitudinal lines of bodies or heads e¹, e², are at right angles 80 with the side lines of the flanges on the U-shaped members, and said members E and F are then pushed or forced up between two of said U-shaped members, (which are placed in pairs). Said member d¹ is then 90 turned one quarter way around with heads e¹ above and heads e² below adjacent lower flanges of said U-shaped members. Heads e¹ then support said member d¹, and heads e² prevent said member from being forced up.

The brick or tile supported by said member d¹ is thereby held in its proper place in the 100 105 110

arch, and can neither be forced above or drawn below its determined position. The proper incline of said brick or tile is obtained by rocking the heads e^1 on the flanges 5 of the U-shaped members on which they rest.

The suspending member d^2 comprises the body member G provided with ratchet teeth g; the elastic members H, bolt h, and the 10 attaching member I. Attaching member I is provided with the hooked ends i, i, which are adapted to engage with the upper flange of an I-beam, as is illustrated in Figs. 2, 4 and 9; and the upper ends of the elastic 15 members H are turned out to rest on the sides of attaching members I when said elastic member is slid in between the parallel sides of said attaching member. The required incline of the brick or tile suspended 20 on said member d^2 , to make said brick or tile fit in the arch, is obtained by slightly twisting attaching member I. Body member G is provided with a slot, corresponding to slot e^3 in member E, and after engage- 25 ment of the upper end of the elastic member H with the desired ones of the ratchet teeth g, bolt h is secured in place. The lower end of the body member G is provided with the head J, and is engageable with the head 30 on the tile or brick which is suspended thereby; and said head J is sufficiently long to permit said brick or tile to extend beyond the I-beam C, so that the additional tile or brick K may be placed on the upper side of 35 the tiles forming the row under said I-beam, to protect said I-beam from the heated products of combustion flowing thereby.

L is a cushion of refractory material, as asbestos, mineral wool, sand, or other suitable material. Cushion L permits some expansion of the fire brick or tile forming the arch.

Where curved supporting beams are used, as M, N, Figs. 3 and 4, the suspending devices d^2 may be used, with element O substituted for attaching element I. Element O is provided with parallel members, (see Fig. 3), corresponding with the parallel members of attaching device I.

50 I claim:

1. In a fire brick or tile arch, the com-

bination of tiles or fire bricks, suspending devices, and supporting beams, said suspending devices comprising elastic members and body members and means to attach said suspending devices to said fire bricks or tiles with said elastic members interposed between said supported tiles and said supporting beams, means to adjust said elastic and body members relative to each other, 60 and means to hold them in said adjusted position.

2. In a fire brick or tile arch, the combination of tiles or fire bricks, supporting beams, suspending devices, means to attach 65 said suspending devices to said supporting beams, and to said fire bricks or tiles, said suspending devices comprising elastic members and body members adjustably interposed between said supported tiles and said 70 supporting beams, said body member provided with a slot, and means engageable through said slot to secure said elastic and body members in an adjusted position.

3. In a fire brick or tile arch, the combination of tiles or fire bricks, suspending devices, supporting beams, and side walls, said suspending devices comprising elastic members and body members, said elastic members attached to said tile and adjust- 75 ably attached to said body members, and lugs on said body members, said lugs adapt- 80 ed to engage with said supporting beams.

4. A fire brick sprung arch suspended from supporting beams, and comprising a plurality of members arranged in a plurality of rows, and respectively provided with projections on the top sides thereof, and a corresponding plurality of suspending means respectively attached to said supporting beams and to a member of said arch, said supporting means respectively comprising an elastic member interposed between said arch members and said supporting beams, said elastic members adapt- 90 ed to engage said projections when said arch members are forced upward into said arch.

CHARLES F. STEVENS.
In the presence of—

T. A. PEEBLES,
CHARLES TURNER BROWN.
